Des. 215,208
Patented Sept. 16, 1969

215,208

VEHICLE BUMPER ATTACHMENT

Lawrence D. Taylor, 4710 Crestview Drive,
Carmichael, Calif. 95608

Filed Nov. 26, 1968, Ser. No. 14,676

Term of patent 14 years

Int. Cl. D12—14

U.S. Cl. D14—6

FIG. 4

FIG. 5

FIG. 6

FIG. 7

FIGURE 1 is a side elevational view of a vehicle bumper attachment, showing my new design, the opposite side being substantially similar in appearance;

FIGURE 2 is a sectional view to an enlarged scale, the plane of the section being indicated by the line 2—2 in FIGURE 1;

FIGURE 3 is a fragmentary sectional view to an enlarged scale, the plane of the section being indicated by the line 3—3 in FIGURE 7;

FIGURE 4 is a bottom plan view;

FIGURE 5 is a front elevational view;

FIGURE 6 is a rear elevational view; and,

FIGURE 7 is a top plan view.

I claim:

The ornamental design for a vehicle bumper attachment, as shown and described.
